POURING APPARATUS

George D. Rogers, Dover, N. J.

Application November 16, 1939, Serial No. 304,728

9 Claims. (Cl. 221—98)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a pouring apparatus.

The purpose of the invention is to provide a pouring apparatus which is particularly applicable to the rapid loading of a molten explosive into projectile bodies.

This purpose is accomplished by means of a pan which is tilted to cause molten explosive to flow into valve-controlled measuring containers before being poured into the projectile bodies.

Further objects are to provide means for separately regulating the temperature of the pan and container so that there will be no appreciable change in temperature of the molten explosive as it passes through the apparatus and to so arrange the valve that the valve stem may be employed to vary the capacity of the measuring containers.

The specific nature of the invention as well as other objects and advantages thereof will clearly appear from a description of a preferred embodiment as shown in the accompanying drawings in which:

Fig. 1 is a view in side elevation of the improved multiple pouring unit.

Fig. 2 is a view in rear elevation.

Fig. 3 is a sectional view through the pouring pan.

Fig. 4 is a plan view of the carriage.

Figs. 5 and 6 are detail sectional views taken on the corresponding lines of Fig. 1.

Referring to the drawings by characters of reference the carriage comprises an upper frame having side bars 5—5 and a plurality of cross bars 6. A plurality of upright brackets 7 on the upper frame each mounts a pair of rollers 8—8 which movably support the carriage from overhead I-beam rails 9. A shaft 10 journaled in bearings 11 on the side bars carries a pair of pinions 12—12 each of which meshes with a rack 13 on the corresponding rail. The shaft is rotated by means of an endless chain 14 passing over a sheave 15 fixed on the shaft.

Depending from each side of the upper frame is an open side frame consisting of a vertical bar 16 and an angled bar 17 having an end extending beyond the vertical bar. The extending ends are connected by a cross bar 18.

A pan 19 has an angle bar 20 extending transversely across its rear side and a similar angle bar 21 on its front side but at a lower level. These bars project beyond the sides of the pan

and the projecting ends on the same side of the pan are connected by a side bar 22 which is spaced from the side wall of the pan to provide accommodation for the bars 16 and 17 of the side frame.

The pan is disposed within the side frames 16—17—18 and is tiltably mounted on trunnions 23 which are in the form of a headed bolt (Fig. 6) passing through the side bar 22, through a bearing 24 in the angled bar 17, and threaded in a reinforcing plate 25 fixed to the pan. The trunnions are positioned near the rear end of the pan so that the front end of the pan will normally drop until its cross bar 21 rests on the cross bar 18 of the frame.

The means for tilting the pan comprises a standard air hoist 26 carried by the upper frame and having a double acting piston 27 with a pair of valve controls indicated at 28. The outer end of the piston is attached to a cross arm 29 positioned directly below the upper frame. A pair of cables 30—30 attached to each end of the cross arm pass over sheave 31 carried by the frame and are connected to a pin 32 (Fig. 5). The pin is carried by a bracket 33 which is pivotally mounted on a bolt 34 which is similar to the trunnion 23 and is mounted in an identical manner in the side bar 22 and reinforcing plate 25.

Referring to Fig. 3 the pan is double walled to provide a chamber or jacket 35 for a heating medium such as steam. The pan is shaped to provide a reservoir 36 at its front lower end and it has a high rear wall 37 providing a trough 38 which becomes operative when the pan is tilted so that molten explosive will flow over the common lip 39. The pan carries a plurality of measuring containers 40 which are arranged in a row adjacent the lip 39 and which are normally in a vertical position when the pan is resting on the frame prior to being tilted. The containers are surrounded by a steam jacket 41 which is independent of the steam jacket of the pan. A steam jacket 42 attached to the under side of the jacket 41 encloses a plurality of pouring spouts 43, one being provided for each container.

Since the molten explosive when poured into the measuring containers would normally tend to lose heat more rapidly than the larger body of the explosive in the reservoir it is desirable to maintain the jacket 41 at a higher temperature than the jacket 35 of the pan. A steam inlet line 44 (Fig. 2) is divided, one branch leading through a valve 45 to the jacket 35 and the other branch to the jacket 41 from which it flows

through line 46 to jacket 42 of the pouring spouts.

Each container 40 is in fluid communication with its pouring spout 43 by means of a beveled opening 47 which may be closed by a valve 48. A valve stem 48a whose size may be altered to vary the capacity of the container extends upwardly through a plate 49 attached to a bracket 50. A spring 51 on each valve normally maintains it in closed position. A shaft 52 mounted in the bracket and rotated by means of a handle 53 carries an actuating finger 54 for each valve stem whereby the valves may be simultaneously opened.

Projectiles 55 which are to be filled with the molten explosive are placed on a stand 56 and are each provided with a funnel 57.

In operation the reservoir of the pan is filled with molten explosive and the valves 47 are closed. The pan is then tilted about its trunnions by operation of the air hoist and the molten explosive in pouring over the lip 39 enters the measuring containers 40, the surplus being caught in the trough 38. The pan is then restored to its normal position, the surplus explosive in the trough flowing back to the reservoir. With the carriage in a position so that the pouring spouts are over a row of shells the handle 53 is actuated to open all of the valves and allow the measured quantity of explosive in each container to flow into its aligned projectile. The carriage is then moved to the next row of projectiles, the valves 47 closed and the metering and dispensing operation repeated.

While the invention has been illustrated in connection with the loading of projectiles with molten explosive it is to be understood that it is applicable to any material which is handled in a similar manner.

I claim:

1. A pouring apparatus comprising a carriage having side frames, a jacketed pan trunnioned in the side frames, said pan having a reservoir and including an upwardly extending rear wall providing a trough, a plurality of measuring containers mounted in the rear wall and open to the trough, a jacket enclosing the containers, a pouring spout on the lower end of each container and having fluid communication therewith, a jacket enclosing the pouring spouts, a valve for closing the lower end of each container and including a stem extending upwardly through the container, means for actuating the valves, means for passing a heating medium through the jacketed members, and means on the carriage for tilting the pan on its trunnions.

2. A pouring apparatus comprising a carriage having side frames, a jacketed pan trunnioned in the side frames, said pan having a reservoir and including an upwardly extending rear wall providing a trough, a plurality of measuring containers mounted in the rear wall and open to the trough, a jacket enclosing the containers, a pouring spout on the lower end of each container and having fluid communication therewith, a jacket enclosing the pouring spouts, a valve for closing the lower end of each container, means for actuating the valves, means for passing a heating medium through the jacketed members, and means on the carriage for tilting the pan on its trunnions.

3. A pouring apparatus comprising a carriage

having side frames, a jacketed pan trunnioned in the side frames, said pan having a reservoir and including an upwardly extending rear wall providing a trough, a plurality of measuring containers mounted in the rear wall and open to the trough, a jacket enclosing the containers, a pouring spout on the lower end of each container and having fluid communication therewith, a jacket enclosing the pouring spouts, a valve for closing the lower end of each container, means for actuating the valves, and means for passing a heating medium through the jacketed members.

4. A pouring apparatus comprising a carriage having side frames, a jacketed pan trunnioned in the side frames and having an upwardly extending rear wall, jacketed measuring containers mounted in the rear wall of the pan, jacketed pouring spouts on the lower ends of the containers, a valve between each container and its pouring spout and including a stem extending upwardly through the container, means for actuating the valves, means for passing a heating medium through the jacketed members, and means on the carriage for tilting the pan on its trunnions.

5. A pouring apparatus comprising a carriage having side frames, a jacketed pan trunnioned in the side frames and having an upwardly extending rear wall, jacketed measuring containers mounted in the rear wall of the pan, jacketed pouring spouts on the lower ends of the containers, a valve between each container and its pouring spout, means for actuating the valves, means for passing a heating medium through the jacketed members, and means on the carriage for tilting the pan on its trunnions.

6. A pouring apparatus comprising a carriage having side frames, a jacketed pan trunnioned in the side frames and having an upwardly extending rear wall, jacketed measuring containers mounted in the rear wall of the pan, jacketed pouring spouts on the lower ends of the containers, a valve between each container and its pouring spout, means for actuating the valves, and means for passing a heating medium through the jacketed members.

7. A pouring apparatus comprising a support, a pan trunnioned in the support and having an upwardly extending rear wall, measuring containers mounted in the rear wall, a pouring spout for each container, a valve between each container and its pouring spout, means for actuating the valves, means for heating the pan, containers and spouts, and means on the support for tilting the pan on its trunnions.

8. A pouring apparatus comprising a support, a pan trunnioned in the support and having an upwardly extending rear wall, measuring containers mounted in the rear wall, a pouring spout for each container, a valve between each container and its pouring spout, means for actuating the valves, and means for heating the pan, containers and spouts.

9. A pouring apparatus comprising a support, a pan trunnioned in the support and having an upwardly extending rear wall, measuring containers mounted in the rear wall, a valve in each measuring container, means for actuating the valves, and means for heating the pan and containers.

GEORGE D. ROGERS.
